UNITED STATES PATENT OFFICE.

RALPH BAGGALY, OF PITTSBURG, PENNSYLVANIA.

SLAG-HEATED BOILER.

SPECIFICATION forming part of Letters Patent No. 746,240, dated December 8, 1903.

Application filed February 14, 1903. Serial No. 143,389. (No model.)

To all whom it may concern:

Be it known that I, RALPH BAGGALY, of Pittsburgh, in the county of Allegheny and State of Pennsylvania, have invented a new and useful Slag-Heated Boiler, of which the following is a full, clear, and exact description, reference being had to the accompanying drawings, forming part of this specification, in which—

10 Figure 1 is a side elevation, partly in vertical section, illustrating my invention. Fig. 2 is a sectional view showing a modified construction of the means for effecting the discharge of the slag from the molds. Fig. 3 is a 15 side elevation, partly in vertical section, showing modified apparatus for coating the molds before they are supplied with slag.

I am aware that heretofore patents have been granted in which it has been proposed to 20 discharge molten slag from smelting-furnaces upon a traveling platform and to convey it through the shell of a steam-boiler; but so far as I know such boilers have never been put into use and the plans proposed have been 25 inherently defective.

The purpose of my invention is to provide 30 an efficient boiler in which the defects of prior constructions are not present; and it consists in the combination, with a boiler, of a slag-conveyer which is arranged to travel through a heating-chamber which is external to the heating-surface of the boiler, but in proximity thereto, the boiler being provided with flues or 35 passages through which the hot gases of the slag and the air which is heated by the slag can pass, the boiler being thus heated not only by direct radiation, but also by the gas and air, which derive heat from the incandescent slag and transmit it to the boiler.

40 The invention also consists in other features described below and summarized in the claims.

In the drawings I show my invention applied to a horizontal boiler of the fire-tube type; but with suitable modifications it can be applied to water-tube boilers and boilers of other design.

2 is the boiler-shell, traversed by tubes 3 and having a stack 4, provided with the usual 45 damper 5.

Beneath the boiler-shell and extending

nearly from end to end thereof is a substantially closed heating-chamber 6, which communicates with the rear end of the tubes 3 and is otherwise preferably closed except for 55 openings 7 at the ends, through which passes the upper branch of an endless chain carrying a series of open trough-shape molds 8, the lower branch of the chain passing through a water-tank 9 below the boiler. 60

10 10 are sprocket-wheels over which the chain passes, and 11 is a spout outside the chamber adapted to supply molten slag to the molds.

12 is a cleaning-door at a convenient part 65 of the chamber 6.

Before the molds pass under the spout 11 they are coated with a refractory wash of lime, clay, or the like mixed with water. The means shown in Fig. 1 for this purpose consists of a 70 tank 13, containing the mixture and provided with a revolving shaft 14, carrying flexible arms 15, of cloth or rubber. The shaft is rotated at a faster rate than the endless chain of molds, so that the arms 15, which travel above 75 and below the surface of the mixture, give several wiping strokes to the surface of each mold as it passes, and thus coat it with the wash. The revolving arms also keep the mixture in the required state of agitation. 80 The purpose of thus coating the molds is to protect them from injury by the slag and to prevent the slag from sticking to them.

In the modified apparatus shown in Fig. 3 the tank 14', which contains the refractory 85 wash, is provided with a rotating paddle 15', which keeps the mixture agitated, and has a discharge-pipe 16, which terminates in an ejector-nozzle 17, directed toward the molds. A pipe 18 discharges compressed air or steam 90 into the nozzle and causes the refractory wash to be discharged in a spray upon the surface of the molds.

In using the boiler the series of molds 8 is driven by power applied to one of the wheels 95 10 and is caused to travel in the direction of the arrow. Molten slag is delivered to the molds as they pass the spout 11, being taken either directly from a smelting-furnace or from an intermediate ladle or receiver. The 100 slag-filled molds pass through the chamber 6 below the boiler, and thus present to the

boiler a hot radiant mass as wide as the boiler and nearly as long, which rapidly heats the water and causes the generation of steam. The hot gases from the slag and the air which 5 enters the chamber through the openings 7 and is heated by contact with the hot surface of the slag on the upper side of the molds and by contact with the hot surface of the molds on the under side pass through the flues 3 10 into the stack, their flow through the stack being regulated by the damper to the rate best adapted to insure the most efficient heating of the boiler. The boiler is thus heated by direct radiation from the hot slag and by con- 15vection of heat by the gases and air which pass from the slag and from the hot molds through the boiler-flues.

When the molds pass from the rear end of the chamber 6, the slag which they contain 20 will have been solidified, and when they pass over the rear sprocket 10 and into the water-tank the sudden chilling of the slag will cause it to disintegrate and the particles will drop upon a conveyer 19, which carries them out 25 of the tank to a car or dumping-place. The molds thence travel through from the tank, past the coating apparatus 13, and under the slag-spout.

When the boiler is used in localities having 30 an abundant supply of water, I may substitute for the tank 9 a pipe 20, Fig. 2, which discharges a stream of water upon the molds after they have emerged from the chamber 6, and thus causes the slag to disintegrate and 35 to drop upon the conveyer 19.

My apparatus renders the operation of the boiler entirely mechanical, and as it provides for the efficient utilization of the slag, which

heretofore has been wasted, it effects a great economy in the working of a smelter plant. 40

The skilled mechanic will be able to modify the apparatus in various ways without departure from my invention, since

What I claim is—

1. A slag-heated boiler having a substantially closed heating-chamber external to the heating-surface, a slag-carrier exposed on its upper and lower surface to the air in the chamber, means for causing the carrier to traverse the chamber, and means for supplying the carrier with molten slag, said boiler having a flue or flues extending from the chamber along the heating-surface to a stack-opening for the passage of the heated air and gases from the carrier and from the slag, 55 whereby the boiler is heated by radiation and convection; substantially as described. 45

2. A slag-heated boiler having a substantially closed heating-chamber external to the heating-surface, a series of molds having disconnected mold-cavities and exposed on their upper and lower surfaces to the air in the chamber, means for causing said molds to traverse the chamber, means for supplying slag thereto, and means for cooling and coating 65 the molds, said boiler having a flue or flues extending from the chamber along the heating-surface to a stack-opening for the passage of the heated air and gases from the molds and from the slag; substantially as described. 70

In testimony whereof I have hereunto set my hand.

RALPH BAGGALEY.
